UNITED STATES PATENT OFFICE.

EDWARD CHARLES MAGNUS, OF BONN, GERMANY, ASSIGNOR TO THE FIRM OF F. SOENNECKEN, OF BONN, GERMANY.

COPYING-MACHINE.

No. 894,025.

Specification of Letters Patent.

Patented July 21, 1908.

Application filed September 30, 1907. Serial No. 395,128.

To all whom it may concern:

Be it known that I, EDWARD CHARLES MAGNUS, a citizen of the United States of America, and resident of Bonn-on-the-Rhine, German Empire, have invented certain new and useful Improvements in Copying-Machines, of which the following is an exact specification.

This invention relates to copying machines of the type in which a band of copying paper perforated or weakened at intervals, is divided or severed into separate sheets by tension.

The present invention has for its object an arrangement by means of which the disconnected sheets, discharged from the copying machine, are piled up smoothly, one on top of the other, without use being made of special operative and movable parts.

It has been proposed before to suspend the moistened copying sheets from a rod or rail, one on top of the other. To attain this end the freely suspended sheets have been moved along by a rail-like part and deposited on a fixed or stationary rail. In the apparatus, as previously constructed, a reciprocating knife served the purpose of the reciprocating rail.

In the present invention for piling up the detached copying sheets only the weight of the moist sheets and the motion the latter receive from the rollers of the copying machine are utilized to the end intended. In the machine the band of paper, provided at intervals with weakened transverse lines or places, for instance perforations, is propelled by means of rollers and a belt or cord or the like, and a pair of rollers discharges the detached copies from the machine. Owing to the weight and flagginess of the moist paper the copy or sheet as it comes from the rollers sinks and takes its course into a sort of trough, the bottom of which it strikes with its free edge. Above this bottom, or support or stop in a certain height an abutment is ar-

anged in the shape of a rod, rail or the like. The sheet, after being in contact with the support offered by the bottom of the trough and receiving further motion from the rollers, is pushed against the abutment and caused thereby to bulge out beyond the same until, finally, when it is released by the rollers its end just released falls beyond the abutment and the sheet straddling the abutment, is thus hung up. As all the copies discharged from the machine are hung up on the afore-

mentioned edge or abutment in the manner described, they form a pile and can be taken off together.

In order to make my invention clearer, I refer to the accompanying drawings, in which a convenient constructional form is illustrated in diagrammatical manner.

Figure 1 is a side elevation, and Fig. 2 a plan view.

The proper arrangement of the copying machine not forming the object of this invention, the machine is illustrated only diagrammatically. In this form, for example, a continuous paper band *s* provided with transverse perforations and supplied from a roller *a*, passes under a guiding roller *b* and between rollers *c d e*. From there the paper passes on to the cords *k*, carried by the rollers *f* and *g*. The roller *g* is connected with the roller *c* by means of a cord or belt. On the roller *g* a roller *h* is placed, to secure the continuous and correct feeding of the sheets from the cords *k*. According to this construction the support and the abutment for piling up the separate sheets or copies are combined and connected by arranging, in front of the rollers *g h* a trough *o*, the bottom *o'* of which forms the support, and the upper edge *o²* the abutment. The sheet separated from the paper band *s* upon issuing from the rollers *g h* sinks into the trough *o* and with its lower edge rests upon the support *o'* formed by the bottom of the trough. In its farther progress the sheet is pushed beyond the abutment *o²* and assuming in succession, the positions shown in dotted lines 1 to 4 finally, on being released by the rollers *g h* is suspended entirely on the edge *o²*, as shown at 5. This operation being automatically repeated as the copies are fed along by the rollers, the sheets are thus correctly and smoothly piled up. In the construction shown, the edge *o³* of the trough *o* is placed in proximity with the roller *g* in such a manner, that the paper, should it by chance adhere to the roller, is detached therefrom by the edge *o³* and led into the trough.

Having thus fully described the nature of my invention, what I desire to secure by Letters Patent of the United States is:—

1. In copying machines of the herein-described type means for collecting separated delivered sheets comprising a trough attached to the discharging end of the copying

machine, the bottom of which trough serves as a support for the front end of said sheets and the upper edge remote from the machine forms a bending bar on which said sheets 5 bend over and collect, for the purpose described.

2. In copying machines of the herein-described type in combination with rotating discharging rollers delivering separated sheets, 10 a trough arranged near the two rollers and with its edge close to the roller, the bottom of said trough serving as a support for the front end of said sheets and the free edge of the trough remote from the machine serving 15 as bending abutment and supporting rail for the paper discharged from the rollers, substantially as described.

3. In copying machines of the herein described type, a support or stop arranged 20 near the discharging end of the machine, an abutment arranged above the support or

stop and near the discharging end of the machine and a detaching device, for preventing the paper from adhering to the lower one of the discharging rollers, for the 25 purpose as described.

4. In copying machines of the herein described type, in combination with discharging rollers, a trough arranged near the two rollers, and bearing with its one edge against 30 the roller (g), for detaching the moist sheet from the roller, the bottom of the trough serving as a support or stop and the free edge of the trough as an abutment for the paper discharged from the rollers, all for the 35 purpose described.

In witness whereof I have hereunto set my hand in the presence of two witnesses.

EDWARD CHARLES MAGNUS.
